UNITED STATES PATENT OFFICE.

WILLIAM FELSTEAD, OF VICTORIA, BRITISH COLUMBIA, CANADA.

HEEL FOR BOOTS AND SHOES.

Application filed April 25, 1923. Serial No. 834,541.

To all whom it may concern:

Be it known that I, WILLIAM FELSTEAD, a subject of the King of Great Britain, and a resident of Victoria, British Columbia, Dominion of Canada, have invented a new and Improved Heel for Boots and Shoes, of which the following is a full, clear, and exact description.

This invention relates to improvements in heels for boots and shoes and has particular reference to a rubber heel construction.

An object of the invention is to provide a heel in which the worn parts thereof may be readily and quickly removed and replaced.

Another object is the provision of a heel wherein one or a plurality of cushioning elements are securely retained in position within a casing or shell and so arranged with respect to the remaining portion of the heel as to combine therewith to form an effective tread surface which will produce a desirable cushioning effect, and at the same time prevent slipping when walking.

A further object is to so dispose the cushioning elements that as the same become worn they may be readjusted and secured to assume their proper relation with respect to the remaining portions of the heel, thus prolonging the usefulness of said elements.

A still further object is to so construct the heel that a plurality of anti-slipping devices may be attached to sections thereof in such manner that said devices may be adjusted to operative or inoperative positions whenever desired.

The above and other objects will appear more clearly from the following detail description, when taken in connection with the accompanying drawing, which illustrates a preferred embodiment of the inventive idea.

In the drawing—

Figure 1 is a top plan view of the heel constructed in accordance with the invention;

Figure 2 is a bottom plan view thereof, partly broken away;

Figure 3 is a longitudinal sectional view;

Figure 4 is a perspective view of one of the anti-slipping devices which may be employed in connection with the invention; and

Figure 5 is a sectional view showing an anti-slipping device in its operative position.

The heel is shown as comprising a casing or shell 4, preferably formed of metal and shaped to conform to the contour of the heel, the upper edge of the casing being provided with a plurality of inturned lugs 5 formed by splitting the material, as indicated at 6. Each of the lugs 5 is provided with a plurality of openings 7, certain of which are utilized to receive fasteners 8 for securing the casing to the upper or inner surface of the lift 9 of the heel, others of said openings being adapted to receive fasteners 10 utilized in securing the heel to the sole 11 of the shoe.

The lift 9 preferably comprises a plurality of superimposed sections 12, although it will be understood that, if desired, this lift may be made in one piece. As shown, the uppermost section 12 of the lift is of the same dimension as the interior of the casing or shell 4, while the lowermost sections 12 are smaller and have their edges spaced from the inner surface of the casing 4 to provide an annular channel or recess 13, the depth of which is equal to the thickness of the three lowermost sections 12 of the lift, the outer surface of the lowermost section being in a plane coincident with that of the lower edge of the casing 4. The portion of the uppermost section 12 forming the inner end of the recess or channel 13 is provided with a plurality of openings 14 for receiving the fastening devices 16 which are utilized to secure the heel to the sole 11.

The recess 13 which extends completely around the three lowermost sections 12 of the lift is designed to receive a plurality of cushioning elements 15 which are preferably made of strips of rubber, there being three of such elements shown in the drawing, (see Figure 2). It will, of course, be understood that these cushioning elements may be combined into a unitary structure without departing from the spirit or scope of the invention. The width of each of the elements 15 is such that the same will fit snugly within the recess 13 and the depth of said elements is greater than that of the recess 13 so that portions of said elements will extend beyond the lower edge of the casing 4 and the lowermost section 12 of the lift, thus combining with said lift to provide an air space 16 in the lower portion of the heel which will be effective in creating a suction to prevent slipping.

The cushioning elements 15 are preferably secured in position by striking from the wall of the casing 4 the inwardly projecting locking tongues 17 which engage the elements in such manner as to prevent displacement thereof. As the lower edges of the cushioning elements 15 become worn to the level of the lowermost section 12 of the lift, the sections may be readjusted to project a portion thereof beyond said lowermost section by first utilizing a suitable tool to disengage the locking tongues 17 from the sections after which another suitable tool may be inserted into openings 18 formed in the wall of the casing 4 and engaged with said sections to move the same outwardly until they are disengaged from the remainder of the heel. Any desirable filling material (not shown) may then be inserted into the recess 13 and packed in the inner end thereof, following which the elements 15 may again be replaced and secured in position by the tongues 17 with portions of said elements projecting below the lowermost section 12.

The heel is so constructed that, if desired, a plurality of anti-slipping devices may be used in connection therewith which will be of especial utility when walking on slippery surfaces. Each of these anti-slipping devices 19 is in the form of a substantially U-shaped body made of a single length of suitable material, the ends of which are sharpened, as indicated at 20. The body is so shaped as to receive between the side members thereof one of the cushioning elements 15, as shown in Figure 5. When the device 19 is in its operative position the web portion 21 of the device will be in engagement with the portion of the uppermost section 12 which forms the inner end of the recess 13 and the sharpened edges of said device will then project slightly below the lower end of the element 15. Should it be found inconvenient or unnecessary to use the

anti-slipping devices, the same may be either entirely removed from the cushioning elements 15, or may be reversed with respect to the position shown in Figure 5, with the web portion 21 in engagement with the lower or tread edges of said elements. In either of the operative or inoperative positions of the anti-slipping devices the sides thereof will be interposed between the three lower sections of the lift and the wall of the casing 4 and thus be securely retained in position.

What is claimed is:

1. A heel for boots and shoes, comprising a casing having its upper end extending inwardly at right-angles and forming means by which the casing can be secured to a boot or shoe, a lift in the casing, the top portion of the lift being of the same dimension as the interior of the casing and engaging the wall and the inwardly extending portion thereof and the remainder of the lift being smaller than the top portion and spaced from the wall of the casing and forming therewith a recess extending entirely around the said casing, a cushion fitting in the recess and extending below the lift and the lower end of the casing and entirely around the heel, and means for securing the cushion in said recess whereby an air space will be formed at the lower part of the heel.

2. A heel for boots and shoes, comprising a shell having at its upper end right angular inwardly projecting and apertured lugs, a lift formed of a plurality of sections, the uppermost section fitting snugly in the shell against the lugs thereof, the remaining sections of the lift being smaller than the first section and forming with the shell an annular recess, cushioning members in the said recess and projecting below the shell and the lowermost lift section, and means for securing the said members in the recess.

WILLIAM FELSTEAD.
